UNITED STATES PATENT OFFICE.

NORMAN W. CUMMINS, OF PLYMOUTH, MICHIGAN, ASSIGNOR TO THE YALE & TOWNE MANUFACTURING COMPANY, OF STAMFORD, CONNECTICUT, A CORPORATION OF CONNECTICUT.

LOCK FOR AUTOMOBILE DOORS.

Application filed April 20, 1926. Serial No. 103,293.

This invention relates to locks for automobile doors, and particularly those used in closed bodies, one object of the invention being to provide a lock operable from the inside of the automobile on three of the doors, in the case of a four door sedan, and on the outside of the fourth door.

The principal object of the invention is to construct the locks in such a manner that the elements thereof will be identical, regardless of whether the lock is used on a right or a left hand door, thereby eliminating the necessity of forming right and left hand elements for the different doors.

Other advantages and details of the invention will be more fully described hereinafter, being clearly illustrated in the accompanying drawings, of which:

Fig. 1 is an outside elevation of a portion of an automobile door and the frame adjacent thereto;

Fig. 2 is a rear elevation of the lock mechanism, the lock having been removed from the door;

Fig. 3 is a sectional plan view taken along the line 3—3 of Fig. 2;

Fig. 4 is a transverse sectional elevation taken along the line 4—4 of Fig. 2;

Fig. 5 is a transverse sectional elevation taken along the line 5—5 of Fig. 2;

Fig. 6 is a sectional elevation taken along the line 6—6 of Fig. 3, and showing the inside lock in its operative position;

Figs. 7, 8, 9, 10, 11 and 12 are detached perspective views of certain of the details of the invention.

Referring to the drawings, my improved lock comprises a base plate 1 adapted to be secured to an automobile door in any suitable manner. Slidably mounted upon the base plate 1 is a main bolt 2 which projects through a rectangular opening 3 provided in a flange 4 of the base plate 1.

The bolt 2 is slidably mounted in a rectangular casing 5, which is provided with projecting tongues 6, adapted to enter apertures 7 in the base plate 1 and thereafter to be turned toward each other upon the outside of the base plate, as shown in Fig. 4, for the purpose of securing the casing 5 to the base plate. The bolt 2 is provided with a rearward extension 8 having a right angle projection 9 integral therewith.

A bolt retracting lever 10 is pivoted at 11

to the base plate 1 and projects upward 55 through an opening 12 in each side of the casing 5, and through a hollow portion 13 formed in the bolt 2, between the bolt proper and the extension 9 thereof.

The casing 5 is rounded at one end, and 60 provides a bearing for an inside abutment lock 14, as shown in Figs. 2 and 3. A follow plate 15 is provided within the casing 5 adjacent the lock 14. Between the plate 15 and the projection 9 of the bolt 2 is provided 65 a spring 16, adapted to project the bolt outwardly from the casing 5.

For the purpose of retracting the bolt from the outside a suitable handle 20 is provided, having a rectangular spindle 21 projecting through the door and at its inner end into a rectangular opening in a cam 22. The cam 22 is adapted to co-operate with a cam lever 23 which is pivoted upon the pivot spindle 11 of the bolt retracting lever 10. 75

The cam lever 23 is shaped as shown in Fig. 9, comprising a body portion 24 and an offset portion 25, said offset portion lying in contact with a flat portion 26 of the cam 22, and a projecting point 27 is provided on said cam for co-operative engagement with the lever 23.

Slidably mounted in the follow plate 15 at one of its ends and in an aperture 28 in the extension 9 of the bolt 2 at its opposite end is a floating bar 30. The bar 30 is provided with a turned end 31, as shown in Fig. 3, which occupies a position adjacent the retracting lever 10, at the side opposite the bolt extension 9, and is engaged on its opposite side by the offset portion 25 of the cam lever 23.

The inside abutment lock 14 is provided with a groove 32 into which the free end of the bar 30 is adapted to project. The lock 14 is provided with a spindle 33 having a flat side 34 adapted to engage a projection 35 provided in bearing aperture 36 in the base plate 1. The projection 35 acts as a stop for the lock 14, whereby the groove 32 in said lock is aligned with the bar 30 as shown in Fig. 2.

As shown in Fig. 6 when the lock 14 is turned to its operative position, the flat portion 34 of the lock spindle engages the projection 35 on its opposite side thereby maintaining the lock 14 with its solid portion adjacent the end of the floating bar 30. 100

With the elements in a position as shown in Fig. 2, should the handle 20 be turned clockwise, the point 27 of the cam 22 will engage the cam lever 23, turning it upon its pivot 11, the said cam lever in turn engaging the projection 31 of the floating bar 30, the projection 31 will engage the bolt retracting lever 10 and the lever 10 will engage the bolt projection 9. Continued rotation of the handle 20 will retract the main bolt 2 to a position within the limits of the flange 4 of the base plate 1. In so doing the end of the bar 30 will be projected into the groove 32 of the bolt 14. Should it be desired to lock the door from the inside, the lock 14 is turned, by means of its handle 37, from the position shown in Fig. 2 to that shown in Fig. 6. In such a position, should the handle 20 be turned, the point 27 of the cam 22 would engage the cam lever 23, and the cam lever 23 would in turn engage the projection 31 of the floating bar 30. Longitudinal movement of the bar 30 would be prevented by means of the end of said bar engaging the solid portion of the abutment lock 14 and, therefore, the main bolt 2 could not be retracted.

In the case of a sedan body having four doors, three of the doors could be locked from the inside in the manner above described, and the fourth door locked by means of a key inserted within a key barrel 40 forming a portion of a barrel lock which may be of any suitable type, forming no part of the present invention and, therefore, being neither illustrated nor described in detail.

The key barrel 40 is rotatably mounted within a stator portion 41 of the lock in the usual manner, and is provided with a spindle 42 which is rectangular in cross-section and adapted to enter a rectangular opening in a rotary lock 43, as shown in Figs. 2 and 4.

The rotary lock 43 is rotatably mounted in a circular opening 44 formed in the base plate 1, and in a circular opening 45 formed in a bridge member 46 secured to the base plate 1. The rotary lock 43 is provided with a groove 47 adapted to receive a key bolt 48, which is slidably mounted in the bridge member 46 and is provided with a downwardly extending projection 49, adapted to enter the space between the cam lever 23 and the retracting lever 10, at a point above the projection 31 of the floating bar 30.

The rotary lock 43 is flattened on one side as illustrated at 50, Figs. 2 and 11, and when the lock is turned clockwise the flattened portion 50 is adapted to be aligned with the top edge of the key bolt 48. The key bolt 48 is provided with a segmental groove 51, into which the body portion of the rotary lock 43, comprising the base of the groove 47, extends when the lock is

turned in a counter-clockwise direction, and as illustrated in Fig. 2.

In the above position any attempt to turn the handle 20 will be resisted by the point 27 of the cam 22 engaging the cam lever 23 which in turn engages the projection 49 of the key bolt 48, the key bolt being prevented from longitudinal movement by the body of the rotary lock 43 extending into the segmental groove 51 of said bolt. 75

The cam 22 is rotatably mounted in a bridge member 52 at one end and in a circular aperture 53 formed in the base plate 1 at its opposite end. The bridge members 46 and 52 are each provided with extended tongues 54 adapted to enter openings 55 in the base plate 1. The opposite end of each of the bridge elements 46 and 52 is provided with a similar tongue 56 which projects through the openings 7, 7 in the base plate 1 occupied by the tongues 6 of the casing 5.

The opening 45 in the bridge member 46 is provided with a limit stop 57 adapted to engage the flat portion 50 of the rotary lock 43 in either of its extreme positions. 90

For the purpose of permitting the introduction of the rotary lock into its bearings the said rotary lock is provided with a notch 58 adapted to pass the stop 57 as the lock is being assembled. 95

As shown in Fig. 2, the bolt 2 and casing 5 are mounted along the horizontal center line of the base plate 1, and it will be noticed that the centers of rotation of the rotary lock 43 and the cam 22 are equally distant 100 from said center line of the base plate 1.

The pivot spindle 11, for the retracting lever 10 and the cam lever 23, is secured in an opening 59 in said base plate, and a second opening 59^a is provided in the base plate 105 equally distant from the center line of said base plate as shown in Fig. 2.

Assuming that the lock as shown in Fig. 2 is adapted to the left hand rear door of a four door sedan, in order to situate the lock on the rear right hand door, all that would be necessary to accomplish the desired result would be to invert the plate 1 and change the pivot spindle 11 from the aperture 59 to the aperture 59^a, and to reverse the positions of the bridge elements 46 and 52 with their respective rotary lock 43 and cam 22. 115

The casing 5 is provided with a similar opening 12 on each of its sides, for the accommodation of the retracting lever, cam lever and key bolt. 120

It will be understood that the detailed construction of the invention is subject to considerable modification without departing from the essential features of this invention, therefore, only such limitations should be placed thereon as are prescribed by the appended claims or necessitated by the prior art of record, and the drawings should not be construed as limiting the invention, be- 125 130

ing provided solely for the purpose of illustrating the preferred form of the invention.

I claim;

1. An automobile door lock, adapted for use on either right or left hand doors and comprising an invertible base plate; a bolt operatively mounted on said base plate at the longitudinal centre thereof; a handle operated retractor for said bolt operable from the outside of said automobile; a mounting for said retractor; identically formed apertures, symmetrically positioned in said base plate, adjacent each side of said bolt, for operatively receiving said retractor and its mounting, at either side of said bolt; and an abutment lock co-operatively aligned with said bolt, on said base plate, operable from the inside of said automobile.

the inside of said automobile.

2. An automobile door lock, adapted for
use on either right or left hand doors and
comprising an invertible base plate; a bolt
operatively mounted on said base plate at the
longitudinal centre thereof; a handle op-
erated retractor for said bolt, operable from
the outside of said automobile; a mounting
for said retractor; identically formed aper-
tures, symmetrically positioned in said base
plate, adjacent each side of said bolt, for op-
eratively receiving said retractor and its
mounting, at either side of said bolt; a ro-
tary lock for said bolt and a mounting there-
for, adapted to be positioned in the set of
retractor receiving apertures at the side of
the bolt opposite that occupied by the re-
tractor and its mounting; and an abutment
lock co-operatively aligned with said bolt,
on said base plate, operable from the inside
of said automobile.

3. An automobile door lock, adapted for use on either right or left hand doors and comprising an invertible base plate; a bolt operatively mounted on said base plate at the longitudinal centre thereof; a handle operated retractor for said bolt, operable from the outside of said automobile; a mounting for said retractor; a retracting lever, operable from the inside of said automobile and pivoted to said base plate; identically formed apertures, symmetrically positioned in said base plate, adjacent each side of said bolt, for operatively receiving said handle operated retractor and its mounting and the pivot of said retracting lever, at either side of said bolt; and an abutment lock co-operatively aligned with said bolt, on said base plate, operable from the inside of said automobile.

4. An automobile door lock, adapted for use on either right or left hand doors and comprising an invertible base plate; a bolt operatively mounted on said base plate at the longitudinal centre thereof; a handle operated retractor for said bolt operable from the outside of said automobile; a mounting for said retractor; a retracting lever, oper-

able from the inside of said automobile and pivoted to said base plate; identically formed apertures, symmetrically positioned in said base plate, adjacent each side of said bolt, for operatively receiving said handle operated retractor and its mounting and the pivot of said retracting lever, at either side of said bolt; a rotary lock, operable from the outside of the automobile, for said bolt and a mounting therefor, adapted to be positioned in the set of retractor receiving apertures at the side of the bolt opposite that occupied by the retractor and its mounting; and an abutment lock co-operatively aligned with said bolt, on said base plate, operable from the inside of said automobile. 70 75 80

5. An automobile door lock, adapted for use on either right or left hand doors and comprising an invertible base plate; a bolt operatively mounted on said base plate at the longitudinal centre thereof; retracting means for said bolt, comprising a cam mounted on said base plate; a cam lever, pivoted to said base plate and adapted to retract said bolt; and identically formed apertures, symmetrically positioned in said base plate, adjacent each side of said bolt, for operatively receiving the elements of said retracting means at either side of said bolt. 85 90 95

6. An automobile door lock, adapted for use on either right or left hand doors and comprising an invertible base plate; a bolt operatively mounted on said base plate at the longitudinal centre thereof; retracting means for said bolt, comprising a cam mounted on said base plate; a cam lever, pivoted to said base plate; identically formed apertures, symmetrically positioned in said base plate, adjacent each side of said bolt, for operatively receiving the elements of said retracting means, at either side of said bolt; and a rotary lock for said bolt adapted to be positioned in the retractor cam receiving aperture at the side of the bolt opposite that occupied by the retractor cam. 100 105 110

7. An automobile door lock, adapted for use on either right or left hand doors and comprising an invertible base plate; a bolt operatively mounted on said base plate at 115 the longitudinal centre thereof; a casing for said bolt secured to said base plate; retracting means for said bolt, operable from the outside of said automobile, comprising a cam; and a cam lever, adapted to retract 120 said bolt; a rotary lock for said bolt; a key bolt, co-operatively associated with said rotary lock; a projection on said key bolt adapted to engage said cam lever; and means for turning said rotary lock, operable from 125 the outside of said automobile.

8. An automobile door lock, adapted for use on either right or left hand doors and comprising an invertible base plate; a bolt operatively mounted on said base plate at 130

the longitudinal centre thereof; a recess in said bolt; a casing for said bolt; recesses in said casing; a handle operated retractor for said bolt operable from the outside of 5 said automobile and comprising a cam and a cam lever; a retracting lever operable from the inside of said automobile, pivoted to said base plate and adapted to pass through the recesses of said bolt and said 10 casing; an abutment lock, co-operatively aligned with said bolt within said casing; a floating bar in said casing, adapted to co-operate with said abutment lock; a projection on said floating bar adapted to lie between 15 said retracting lever and said cam lever; and a spring within said casing for projecting said bolt.

9. An automobile door lock, adapted for use on either right or left hand doors and 20 comprising an invertible base plate; a bolt operatively mounted on said base plate at the longitudinal centre thereof; a handle operated retractor for said bolt operable from the outside of said automobile; a rotary lock 25 for said bolt, operable from the outside of said automobile and comprising a cylindrical member rotatably mounted at one of its ends in a circular aperture formed in said base plate; a bridge element secured to the base 30 plate and having an aperture adapted to receive the opposite end of said cylindrical member; a flat side formed on said cylindrical member; a key bolt slidably mounted in said bridge member adjacent said cylindrical member and having a concavity 35 formed in its edge adjacent the said cylindrical member; means for turning the said cylindrical member to move the flat side thereof into alignment with the adjacent 40 edge of said key bolt or the curved portion of said cylindrical member into the concavity of said adjacent edge of said key bolt, and a limit stop for said rotary lock comprising a projection in the opening of said

bridge member adapted to engage either end 45 of the flat portion of said cylindrical member when the said cylindrical member is turned to either of its said positions.

10. An automobile door lock, comprising a base plate; a bolt operatively mounted on 50 said base plate; a casing for said bolt in which said bolt is adapted to slide; means for retracting said bolt; an abutment lock in said casing; and means co-operative with 55 said retracting means and said abutment lock, for preventing the retraction of said bolt.

11. An automobile door lock, comprising a base plate; a bolt operatively mounted on 60 said base plate; a casing for said bolt; retracting means for said bolt operable from the outside of the automobile and including a cam and a cam lever; an abutment lock in 65 said casing comprising an apertured cylinder operable from within the automobile; a floating bar in operative engagement with said cam lever adapted to move into the cylinder aperture when the bolt is retracted, and a spring for forcing the bolt outward.

12. An automobile door lock, comprising a 70 base plate; a bolt operatively mounted on said base plate; a casing for said bolt; retracting means for said bolt operable from the outside of the automobile; a spring in 75 said casing for moving the bolt outward; an abutment lock in said casing comprising a cylinder; an aperture in said cylinder; a floating bar in said casing between the retracting means and the abutment lock, adapted to normally enter said aperture 80 when the bolt is retracted; means for turning the abutment lock to present a solid portion of said cylinder adjacent the end of the floating bar, for resisting retraction of the bolt; and means for securing alignment 85 between the bar and the aperture or the bar and the solid portion of said cylinder.

NORMAN W. CUMMINS.
